Inventor:
Alfred J. Thomson,
by Walter G. Lombard,
Atty.

UNITED STATES PATENT OFFICE.

ALFRED J. THOMSON, OF CANTON, MASSACHUSETTS.

CLEAT.

Application filed September 22, 1922. Serial No. 589,920.

To all whom it may concern:

Be it known that I, ALFRED J. THOMSON, a citizen of the United States of America, and a resident of Canton, in the county of Norfolk and State of Massachusetts, have invented certain new and useful Improvements in Cleats, of which the following is a specification.

This invention relates to cleats or cord fastening devices for use on the frames used by tanners for stretching and treating hides, and has for its object the production of a simple device readily attached to the frame and which will securely hold the toggle cord and prevent any slipping thereof.

The invention consists of a one-piece cleat formed of bent wire and provided with eyes by which it may be secured to the frame by screws or nails, said cleat consisting of two substantially parallel portions, interposed between said extending from the said eyes, and having at their opposite ends reverse bends forming acute angles with said parallel portions, these reversely bent portions being connected together by a cross member.

The invention further consists in forming said parallel portions with upward bends beneath said cross member, the space between said bends and cross member being less than the diameter of the toggle cord used.

The invention further consists in forming said cleat with the eyes and forward end of the parallel portions in the same plane with the reversely bent portions angularly disposed relatively thereto.

The invention further consists in certain novel features of construction and arrangement of parts which will be understood readily by reference to the description of the drawings and to the claims to be herein-after given.

For the purpose of illustrating the invention, one preferred form thereof is shown in the drawings, this form having been found to give satisfactory and reliable results, although it is to be understood that the various instrumentalities of which the

invention consists can be variously arranged and organized, and that the invention is not limited to the precise arrangement and organization of the instrumentalities as herein shown and described, except as required by the scope of the appended claims. Of the drawings:

Figure 1 represents a plan of a cleat embodying the principles of the present invention, shown attached to a portion of the hide-stretching frame. 80

Figure 2 represents a front elevation of the same, and

Figure 3 represents a side elevation of the same.

Similar characters indicate like parts throughout the several figures of the drawings.

In the drawings, 10, 10 are two parallel portion of a cleat formed of one piece of wire, these parallel portions 10, 10 being separated from each other as indicated in Figure 1 of the drawings.

One end of the parallel portions 10, 10 have laterally extending portions 11 on the ends of which are formed eyes 12 by which the cleat may be secured by means of nails or screws 13 to a hide-stretching frame 14.

The opposite ends of the parallel portions 10, 10 have reverse bends 15 formed therein from which the parts 16 extend toward the eyes 12, the opposite ends of these parts 16 being connected by means of a member 17.

Beneath the member 17 the parallel portions 10, 10 of the cleat are each provided with an upward bend 18, the distance between these bends 18 and the connecting member 17 being less than the diameter of the toggle cord 19 adapted to coact with the cleat.

The reversely extending parts 16 are at an acute angle to the parallel portions 10, 10, thereby forming a pair of notches, the walls of which are adapted to impinge upon the cord 19 when inserted in said notches.

The parts 16 are also positioned at an angle to the face of the frame 14, the ends nearest the eyes 12 being a greater distance from the face of the frame 14 than the op-

posite ends connected to the parallel portions 10 by means of the reverse bends 15. These parallel portions 10, the laterally extending parts 11, and eyes 12 are adapted to be positioned flat upon the surface of the frame 14, except where the bends 18 extend upwardly therefrom.

When it is desired to stretch a hide upon the frame, a toggle of any well known construction is secured to the hide and the cord 19 thereof is then adapted to be secured to the cleat and held securely in position during the stretching of the hide and treating thereof.

15 When the toggle has been secured to the hide, the cord is pulled and forced over the upward bends 18 beneath the cross member 17. The cord is then still further pulled until it is positioned as indicated in dotted 20 lines on Figure 1 of the drawings, in the notches formed by the members 10, 15, and 16. This will cause the cord to be gripped and it will be held in position under ordinary circumstances, but it has been found 25 in practice that it is desirable to get an additional grip upon the cord in order to more firmly hold it in position. This is accomplished by having the parallel portions 10, 10 in one plane and the parts 16 in a plane 30 at an angle to the plane in which the portions 10, 10 are located, i. e., inclined upwardly from the reverse bends 15, as indicated in Figure 3.

By thus constructing the cleat, the cord 35 passes under the parts 16 and over the portions 10, 10 making a bend in the cord which, in addition to the grip due to the cord being wedged between the parts 10, 16, locks the cord so that all slipping thereof 40 in the cleat is absolutely prevented.

By making the eyes 12 at some distance 45 outside of the parallel parts 10, and connected thereto by means of the parts 11, the cord may be pulled taut in the cleat, the parts 11 yielding slightly under the strain, and when the cord has been released the 50 cleat being formed of resilient wire, the parts 11 will spring back into their normal position as indicated in Figure 1 of the drawings, giving a slightly additional pull upon the free end of the cord, to the opposite end of which is attached the usual toggle secured to the hide being stretched.

By making the cleat in this manner, there 55 is no danger of breaking the wire at the bends 15, as it has been found in practice will happen with cleats in which the parts 16 are located directly over the parallel parts 10, as is shown in an earlier Patent 60 No. 880,764 issued to me March 3, 1908.

This makes a very effective form of cleat which is simple to construct and by which the toggle cord may be securely held in position during the stretching of the hide.

It is believed that the operation and many 65 advantages of the invention will be readily understood without further description.

Having thus described my invention, I claim:

1. A cord-holding cleat formed of a single piece of wire bent into shape and comprising two eyes; at the opposite ends of said wire parallel portions extending from said eyes; reverse bends at the opposite ends of said parallel portions extending outwardly toward said eyes and at an acute angle to said parallel portions; and a cross member connecting said reversely bent portions.

2. A cord-holding cleat formed of a single piece of wire bent into shape and comprising two eyes; at the opposite ends of said wire parallel portions extending from said eyes and having upward bends therein; reverse bends at the opposite ends of said parallel portions extending outwardly toward said eyes and at an acute angle to said parallel portions; and a cross member connecting said reversely bent portions and positioned above the upward bends in said parallel portions a distance less than the diameter of a toggle cord to be used therewith.

3. A cord-holding cleat formed of a single piece of wire bent into shape and comprising two eyes; at the opposite ends of said wire parallel portions extending from said eyes and adapted to rest upon a hide-stretching frame; reverse bends at the opposite ends of said parallel portions extending outwardly towards said eyes and at an acute angle to said parallel portions, said reversely extending portions being inclined upwardly away from said frame; and a cross member connecting said reversely bent portions.

4. A cord-holding cleat formed of a single piece of wire bent into shape and comprising two parallel portions spaced apart; a cross member above said parallel portions and spaced therefrom with the opposite ends extending outwardly beyond said parallel portions; inclined portions connecting the opposite ends of the cross member with one end of said parallel portions; and means at the opposite end of said parallel portions for securing the cleat to a hide-stretching frame.

5. A cord-holding cleat formed of a single piece of wire bent into shape and comprising two parallel portions spaced apart; a cross member above said parallel portions and spaced therefrom; with the opposite ends extending outwardly beyond said parallel portions; inclined portions connecting the opposite ends of the cross member with one end of said parallel portions; and eyes connected by laterally extending parts to the opposite end of said parallel portions.

6. A cord-holding cleat formed of a single piece of wire and comprising eyes at the opposite ends thereof; parallel portions extending from said eyes and adapted to rest upon a hide stretching frame; a cross member above and spaced from said parallel portions with its opposite ends extending outwardly beyond said parallel portions; and portions extending downwardly from

the opposite ends of said cross member and 10 inclined inwardly, connecting with said parallel portions by reverse bends.

Signed by me at Boston, Mass., this 20th day of September, 1922.

ALFRED J. THOMSON.
